ONE-PIECE RAIL ANCHOR

Ralph W. Payne, Washington, D.C., assignor, by mesne assignments, to Poor & Company, Chicago, Ill., a corporation of Delaware

Application January 30, 1957, Serial No. 637,207

1 Claim. (Cl. 238—327)

This invention relates to Rail Anchors and more particularly to the general type of One-Piece Rail Anchor shown in Patent No. 1,559,589.

The above type of rail anchor may be briefly described as comprising a low carbon steel bar of rectangular cross section formed at one end with a hook-shaped bend adapted to exert gripping pressure on the top and bottom surfaces of a base flange of a railway rail at one side of the rail. The other end of the bar is offset to provide a locking shoulder for engaging an edge surface of a base flange at the other side of the rail, and the portion of the bar intermediate the said hook and said locking shoulder is bowed downwardly relative to the rail so as to abut against a vertical face of an adjacent crosstie at a substantial distance below the rail base.

The above type of rail anchor, as heretofore made, provides a strong wedging grip on the base portion of a rail, but it is not entirely satisfactory, since it is necessary, for purpose of economy, to form such anchor from a low carbon steel bar of substantially the cross-section hereinafter specified to provide it with the desired holding power.

It has been customary, in the manufacture of the above type of anchor device, to form it from a bar of rectangular cross section having a horizontal width of approximately $\frac{3}{8}$ inch and a vertical thickness of approximately $1\frac{1}{8}$ inches. This width of bar provides the anchor device with rail gripping surfaces of optimum width for exerting firm frictional grips on the rail base without likelihood of slippage lengthwise of the rail and without likelihood of undesirable turning of the anchor about a horizontal axis when the downwardly bowed portion thereof is pressed against a vertical face of a crosstie. The vertical thickness of $1\frac{1}{8}$ inches is approximately the maximum useable thickness which will afford the necessary flexibility of the hook portion of the anchor to enable a workman to drive it onto the base flange of a rail without likelihood of flexing the hook portion thereof beyond its elastic limit.

The principal object of the present invention is to provide improvements whereby an anchor of the above type may be made of less weight and, at the same time, maintain rail gripping surfaces of said optimum width and to make it practical to increase the effective vertical thickness of the anchor so as to increase its holding power, but will not require increased manual force to apply the anchor to a rail.

A further important object of the present invention is to provide a structure which will accomplish the above stated improved results and which will facilitate the manufacture of the improved anchor device by the use of conventional equipment and in harmony with standardized rolling mill practices and tolerances.

Prior efforts have been made by others to provide similar improvements with the view of reducing the weight of such anchor device and, at the same time, maintain its highly efficient resilient wedge grip on the rail. In some instances the said proposed improvements have

2

contemplated the use of low carbon channel bar stock, but the results obtained thereby have not been satisfactory, since the proposed improvements could not be produced without radical departures from established rolling mill practices and tolerances. Furthermore, the cross section of the channel bar stock heretofore proposed has usually been such that the side flanges thereof project upwardly from the base web of the channel for greater distances than the vertical thickness of said base web. Consequently the body of metal in the base web of such channel is insufficient to transmit enough heat to the flanges of the bar to maintain them sufficiently pliable to respond to the stretching and compression forces developed during the bending of the bar around a forming die. Because of the rapid cooling of the flanges of a deep channel bar, that is to say a channel bar in which the height of the said flanges, measured from their junction with the base web of the channel, is greater than the thickness of said base web, the cooler outer edges of the side flanges resist stretching thereof during the bending of the hook portion of the bar and therefore tend to move laterally from their perpendicular positions to semi-collapsed angular positions. When the flanges assume said semi-collapsed angular positions, they no longer perform their intended rigidifying function.

A preferred embodiment of the invention is shown in the accompanying drawings wherein:

Fig. 1 illustrates a face view, in elevation, of a rail anchor device constructed in accordance with this invention, the anchor being illustrated in its applied position on a base portion of a railroad rail;

Fig. 2 is a plan view of the structure shown in Fig. 1; Fig. 3 is a sectional view taken substantially on line 3—3 of Fig. 1;

Fig. 4 illustrates, on a larger scale, a cross section of a metal bar used in the manufacture of the improved rail anchor;

Fig. 5 is a fragmentary face view of one end of the rail anchor applied to a base flange of a railroad rail, the view being shown on a larger scale to better illustrate a principal feature of the improved construction;

Fig. 6 is an end view of the structure shown in Fig. 5 illustrating in dot-and-dash lines the manner in which the side flanges of the hook portion of the anchor are momentarily deflected laterally to relieve the tensile stresses in the hook portion thereof during the applying movement of the anchor onto a rail base; and

Fig. 7 is a fragmentary sectional view of a portion of a conventional apparatus utilized to bend the bar into the desired configuration.

Referring to the drawings: 10 designates the base portion of a railroad rail, 11 an underlying crosstie on which the rail is supported, 12 a conventional form of tie plate interposed between the top surface of the crosstie 11, and the bottom surface of the rail base 10, and 12 designates, as a whole, the improved rail anchor constructed in accordance with this invention and applied to the base portion of a rail in a position to abut against a vertical side face of the crosstie.

The improved rail anchor 12 is a so-called heavy bar one-piece type of device, since it is made from a heavy bar of low carbon steel as distinguished from the use of the lighter weight and more expensive high carbon steel. It may be described generally as comprising a low carbon steel bar formed at one end with a hook-shaped bend 13 to provide upper and lower jaws 14 and 15 for frictionally gripping the top and bottom surfaces of a base flange 16 of a rail at one side thereof. The other end of the bar is offset to provide a locking shoulder 17 to engage an edge surface 18 of the base flange 19 at the other side of the anchor construction was not entirely satisfactory on the rail. The portion of the bar intermediate

the lower jaw 15 and the said locking shoulder is bowed downwardly relative to the bottom surface of the rail base 10 to provide a tie abutting portion 20 for engaging a vertical face of the crosstie 11 at a substantial distance below the rail base.

Rail anchors of the above class, as heretofore produced on a commercial scale, have been usually made from rectangular bar stock having a horizontal width of approximately $\frac{3}{8}$ inch and a vertical thickness of approximately $1\frac{1}{8}$ inches. The rectangular section of bar was adopted for use, rather than other shapes, since the rectangular section simplified the bending operations. The bending pressure, in such case, could be applied directly to an outer flat face of the bar rather than at other locations. Also, the heated bar, being of a substantial thickness, remained uniformly pliable throughout the bending operation.

While the above features were highly desirable in that they facilitated the manufacture of the anchor device, the anchor construction was not entirely satisfactorily since it did not provide for economical distribution of the metal. Various unsuccessful efforts have been made to overcome this objection. In some instances the use of channel bar stock has been proposed with the view of increasing the effective vertical thickness of the bar and thereby increase the holding power of the anchor device. However, these various proposals have contemplated the use of a bar of the conventional width and thickness, approximately $\frac{3}{8}$ inch in width and $1\frac{1}{8}$ inches in vertical thickness, provided with a deep channel, that is to say a channel having side flanges of greater height, measured from their junction with the base web of the channel, than the vertical thickness of the base web of the channel. Consequently such rail anchors were unsatisfactory, since a bar of such conventional width used in the manufacture of such anchor devices cannot be satisfactorily made, on a production scale, with a deep channel formed therein. Furthermore, such deep channel, regardless of the manner in which it is formed in a bar of the above conventional width and vertical thickness must necessarily comprise thin side flanges of substantial height as compared with the overall width and thickness of the bar. These flanges cool very rapidly during the bending operations performed on the bar and, therefore, present the several objections mentioned in the introductory part of the present application.

The present invention contemplates forming the anchor device from channel bar stock, but the specific configuration of the channel bar stock is such that it avoids the various objections herein mentioned with respect to the channel bar stock heretofore used.

The preferred section of channel bar stock embodied in the present invention is shown in Fig. 4. It comprises a bar formed with a channel 21 in its top face, the opposite sides of which are defined by side flanges 22, 23, the heights of which measured from their junction with the base web 24 of the channel are approximately one-half the vertical thickness of said base web. The inner and outer faces 25, 26 of the side flanges converge toward their upper edges so that the thickness of the flanges progressively decrease toward said upper edges. The outer faces of the flanges are also inclined inwardly. The bottom of the channel is formed with a continuous curve which merges into the inner faces of the side flanges. The bottom surface 27 of the bar has rounded corners and defines the width of the rail gripping surfaces 28, 29 and 30.

According to the present invention, the heights of the side flanges of the channel stock measured from their junction with the base web 24 of the bar approximate only $\frac{1}{3}$ of the overall vertical thickness of the bar. This construction presents a distinct advantage during the bending of the bar into the desired hook-shaped configuration shown in Fig. 1, in that the large body of metal constituting the base web 24 of the bar transmits sufficient heat

to the side flanges 22, 23 to maintain them pliable and thereby permit them to respond to the stretching and compression forces developed during the bending of the heated bar around a forming die, for example the anvil die 35 shown in Fig. 7. By maintaining the flanges 22, 23 pliable they are not subjected to the forces which otherwise tend to force them into lateral angular positions.

The anchor device, when constructed from the improved stock above described, provides greater strength per unit weight as compared with anchors of this type heretofore made from bar stock of rectangular cross section of similar width and vertical thickness. Also, the flexibility of the hook portion 13 is greater than that of a solid rectangular bar of comparable vertical thickness, since the side flanges of the improved bar on the outer side of the neutral axis of the bend are bowed outwardly in response to the compression forces developed by the spreading of the hook as it is driven onto the base flange 16 of the rail. The outward deflection of the said flanges are indicated by the dotted lines 32 in Fig. 6. This deflection, however, is only momentary during the application of driving force to the hook portion, but it serves to move the tensile area toward the inner face of the bend by momentarily shifting the neutral axis of the bend from the dotted position NA-1 shown in Fig. 5 to the dotted position NA-2 and thereby momentarily reduce to a minimum the stresses incident to the spreading of the hook as it is driven onto the base flange of the rail. The flexing or spreading of the upper jaw 14 relative to the lower jaw is very slight, as shown in dotted line 33 in Fig. 1, the dotted line representing the normal position of the upper jaw before the anchor is applied to a rail. It will be seen, therefore, that the maximum expansion of the hook is relatively small as compared to the end opening of the hook. This condition is maintained because of the fact that the bar is composed of low carbon steel and, therefore, has a relatively low elastic limit as compared to the elastic limit of higher carbon spring steel.

The manner in which the bar stock is bent into the desired configuration is illustrated in Fig. 7 of the drawings. The bar is first bent to an intermediate position in a breakdown die (not shown) in which it is bowed to form the tie abutting portion 20 and in which the end 34 is bent to the angular position shown in Fig. 7 by the dot-and-dash lines. The partially bent bar is then placed on the anvil portion 35 and is clamped thereto by a pressure head 36. The end 34 of the bar is then engaged by a wing arm 37 and bent around the anvil die 35 until it assumes the full line position shown in Fig. 7. The wing arm 37 is preferably provided with rollers 38 which ride on suitably positioned trackways 39 and the end 40 of the wing arm presses against the outer edges of the side flanges 22, 23 of the bar during the entire bending operation. When the wing arm reaches its final position sufficient pressure is developed at the end 40 thereof to indent the side flanges as indicated at 41 and thereby insure firm contact of the surface 28 of the bar against the inclined under-surface 42 of the anvil die.

I claim:

A rail anchor comprising a rolled metal bar bent at one end into a hook adapted to be expanded into elastic clamping contact with the top and bottom surfaces of a base portion of a railroad rail at one side of the rail, locking means at the other end of the bar for engaging an edge portion of the rail base at the other side of the rail, and a downwardly bowed tie abutting portion intermediate said hook and said locking means; the said anchor bar being of channel configuration in cross-section with the base of the channel being composed of a rectangular body of metal having perpendicular side faces and having a vertical height equal to the width of the anchor and the sides of the channel being defined by flanges which are perpendicular to the base of the channel each of which has a height substantially equal

to one-half the vertical thickness of said base portion of the channel and with the inner and outer side faces of each flange inclined toward each other to provide a substantially balanced progressively increased distribution of metal from the top to the bottom of the flange at opposite sides of a plane perpendicular to said base and which bisects the angle between said opposite sides of each flange to resist lateral displacement of the flange during the bending of the bar and to provide the flange at its junction with the base of the channel with a width substantially equal to one-half of the width of the anchor

to provide rigidity and to insure ready transfer of heat from the said rectangular body of metal constituting the base of the channel into and throughout the height of the flange so as to avoid the development of flange displacement lateral stresses.

CERTIFICATE OF CORRECTION

Patent No. 2,936,127

May 10, 1960

Ralph W. Payne

It is hereby certified that error appears in the printed specification of the above numbered patent requiring correction and that the said Letters Patent should read as corrected below.

Column 2, lines 71 and 72, for "anchor construction was not entirely satisfactory tion" read -- rail and thereby lock the anchor in its applied position --; column 3, line 20, for "satisfactorily" read -- satisfactory --.

Signed and sealed this 11th day of October 1960.
